UNITED STATES PATENT OFFICE.

GIOVANNI PASSEFIUME, OF PORTLAND, OREGON.

SHOE-DRESSING MACHINE.

Application filed May 27, 1926. Serial No. 112,038.

My invention relates to shoe machinery and has particularly to do with the rotary tool referred to as a heel breaster, which is the tool used to dress the concave surface of a heel and is frusto-conical in shape.

It is common practice at the present time to fasten over said frusto-conical head a piece of sandpaper and to fasten the latter in place by a threaded nut arranged to grip one portion thereof and grip the same tightly against said head.

It is impractical to use a similarly formed cup-wheel made of emery or similar abrasive material for this purpose, because the leather 15 ground away by said wheel soon fills up the interstices in said wheel, and forms a glazed surface thereon. Said surface can only be rendered effective again with great difficulty and corresponding waste of time.

20 Sand paper or emery cloth on the other hand is easily torn and is worn out very quickly, the expense and loss of time entailed in the frequent replacement of said sheets of abrasive material being a factor of 25 considerable importance.

The object of my invention therefore, is to provide an abrasive attachment for rotary heads of this character by which the expense, trouble and loss of time incident to the frequent replacement or dressing of the active 30 abrasive surface of such heads will be greatly minimized.

I attain this object by providing a metallic plate formed as the segment of a ring and 35 having thereon a plurality of upstanding, cutting blades preferably formed of struck-up portions of said plates. The blades thus formed constitute abrasive or cutting surfaces which will last for a considerable period 40 without replacement, because wear merely dresses their height but maintains a sharp cutting edge thereon. For example, it is the usual practice to replace the strip of sandpaper upon the wheel breaster every day or 45 every other day, but metallic plates embodying my invention will serve effectively for several months, without attention.

I am aware that machines of the type shown in Patent No. 1,054,656, granted 50 February 25, 1913 to Ronald F. McFeely, are old in the art.

55 My invention is an improvement over the head shown in said patent in the following particulars:

1. My improved metallic abrasive sheet is adapted to be fastened to a rotary head by a

single adjustable member, is simply and easily mounted and dismounted, which factor is of considerable importance especially when plates having differently formed teeth are used upon the same for "roughing" and "finishing" work. 60

2. The upstanding blades in my invention are flat and will thus cut uniformly independently of their height, thus being 65 substantially unaffected by wear.

3. The upstanding blades in my invention are staggered and are arranged to cover the entire length of the active surface of the head and thus the shoe being dressed will 70 not have to be moved to and fro, to prevent the formation of grooves upon the surface being finished.

Further details and advantages of my invention are hereinafter brought out, and are 75 described with reference to the accompanying drawings, in which:

Fig. 1 is a perspective view of a rotatably mounted head covered with an abrasive sheet embodying my invention; 80

Fig. 2 is a plan view of said sheet arranged flatwise; and

Fig. 3 is a longitudinal section thru said head and sheet showing the mode of fastening the latter to the former. 85

My improved abrasive sheet *a* is formed to constitute an attachment to a standard frusto-conical head *b* commonly provided at one end of the main driving shaft *c* of a shoe machine. Said head is fastened to said shaft at its end of lesser diameter and is coaxial therewith. Adjacent the point of juncture of said shaft *c* with said head *b*, a nut *d* is mounted upon the threaded portion *c'* of said driving shaft. 90

The nut *d* is arranged to clamp a sheet of abrasive material wrapped about the head *b* to the latter. The sheet of abrasive material *a* embodying my invention is formed as a segment of a ring and is provided with a series of substantially flat struck-up portions *a'* forming blades. That is, said blades *a'* are merely portions of the sheet *a* which have been severed upon one side and forced up cup-shaped to the remainder of 100 the sheet upon the remaining three sides. 95

As can be noted in Fig. 2 said blades *a'* extend radially to the center of curvature of said sheet and when the latter is rolled and wrapped about the head, as shown in Fig. 1, 110 extend substantially in longitudinal alignment with the axis of rotation of said head

and the blade portions a' extend outwardly from the head at right angles and substantially radially to said axis.

As can be noted in Fig. 2, said blades a' are formed in circular rows and the blades in the adjacent rolls are staggered relatively, and overlap the lines of termination of the blades in the adjacent rows so that the entire active length of the plate serves as an abrasive medium. That is, when the head is used to dress an article the blades cover substantially the entire active surface of the head so that the shoe being dressed may remain stationary without having grooves formed therein.

The portion of the plate of lesser radius, as shown in Fig. 2, has a strip a^2 which is unperforated, this being the portion of the plate gripped by the nut d , as shown in Fig. 3.

The head b is covered for the greater part with a layer of felt e and the abrasive sheet, which is relatively flexible, is thus permitted to give slightly to conform to irregularities of the article being dressed thereby.

I claim:

1. In a shoe dressing machine, the com-

bination of a rotatable head, a driving shaft co-axial therewith, and an abrading member mounted upon the periphery of said head, said member having a plurality of spaced upstanding blade-like projections constituting shearing blades extending in a row across its face and in a series of rows, the blades in each row being opposite to and overlapping the spaces between the blades in the preceding and succeeding rows.

2. An attachment for a shoe dressing machine, the latter comprising a rotatable frusto-conical head, a driving shaft co-axial therewith, and joined to the face thereof of lesser diameter, and a threaded nut carried by said shaft at its point of juncture with the head, such attachment consisting of a segmental ring-like plate member having a plurality of struck-up elongated cutting blades of substantially uniform height, arranged in rows, the blades in each row being opposite to and overlapping the spaces between the blades in the preceding and succeeding rows and extending upon lines substantially radial to the center of curvature of the ring-like segmental member.

GIOVANNI PASSEFIUME.
